(57) CLAIM

We claim the ornamental design for a handgrip for a sports pole, as shown and described.

DESCRIPTION

FIGS. 1-8 are views of a first embodiment of a handgrip for a pole, a sports pole such as a ski pole or a walking pole, or the like, showing our new design and, more particularly: FIG. 1 is a rear and left side perspective view of a handgrip for a sports pole showing my new design;

FIG. 2 is a front and left side perspective view thereof;

FIG. 3 is a left side elevation thereof;

FIG. 4 is a right side elevation thereof;

FIG. 5 is a rear elevation thereof;

FIG. 6 is a front elevation thereof;

FIG. 7 is a top plan view thereof; and,

FIG. 8 is a bottom plan view thereof.

The broken line showing in the figures is for illustrative purposes only and forms no part of the claimed design.
